UNITED STATES PATENT OFFICE.

RICHMOND LANE CHIPMAN, OF AKRON, OHIO.

DESIGN FOR TILING.

SPECIFICATION forming part of Design No. 36,558, dated September 15, 1903.

Application filed August 10, 1903. Serial No. 169,042. Term of patent 14 years.

To all whom it may concern:

Be it known that I, RICHMOND LANE CHIPMAN, a citizen of the United States, and a resident of Akron, county of Summit, and State of Ohio, have invented a new, original, and ornamental Design for Tiling, of which the following is a specification, reference being had to the accompanying drawing, forming a part thereof.

10 The figure is a plan view of tiling, showing my new design.

What I claim as new, and desire to secure by Design Letters Patent, is—

The ornamental design for tiling, as shown.

In testimony whereof I have signed my name to this specification, in the presence of two subscribing witnesses, this 7th day of August, 1903.

RICHMOND LANE CHIPMAN.
